UNITED STATES PATENT OFFICE.

FREDERICK G. OSBORN, OF NEWARK, NEW JERSEY, ASSIGNOR TO EBERHARD FABER, OF NEW YORK, N. Y.

DESIGN FOR AN ERASER-HOLDER.

SPECIFICATION forming part of Design No. 18,003, dated January 3, 1888.

Application filed November 11, 1887. Serial No. 254,931. Term of patent 7 years.

To all whom it may concern:

Be it known that I, FREDERICK G. OSBORN, of Newark, in the county of Essex and State of New Jersey, have invented a new Design 5 for Eraser-Holders, of which the following is a specification.

This design relates to the shape and configuration of the hollow holder for erasive rubber. The design of the shape and configuration of such holder is represented in the accompanying drawings, in which—

Figure 1 is an elevation of the two parts of the holder. Fig. 2 is a vertical section of the same, and Fig. 3 is an end view of the holder.

15 The holder is cylindrical in shape and in two parts, A and B, the size being such that one part will slip within the other. The erasive rubber is represented at c. The shape of the part A at the closed end 2 is tapering, as

represented, and the shape of the part B at the 20 closed end is flat, with a projecting knurled bead around the edge at 3.

This holder is neat and artistic in its appearance, and the surface is usually polished.

I claim—

25 The design for an eraser-holder of the shape and configuration shown, consisting of the two-part hollow cylindrical case having a tapering closed end on one part and a flat closed end on the other part, with a knurled 30 bead around the edges, all substantially as shown.

Signed by me this 4th day of November, 1887.

FRED. G. OSBORN.
